(57) **CLAIM**

The ornamental design for a patella clamp, as shown and described.

DESCRIPTION

FIG. 1 is a front perspective view of a design of one embodiment of the patella clamp;

FIG. 2 is a first side elevation view of the patella clamp of FIG. 1, the second side elevation view of the patella clamp being a mirror image of the first side elevation view shown in FIG. 2;

FIG. 3 is a rear elevation view of the patella clamp of FIG. 1;

FIG. 4 is a front elevation view of the patella clamp of FIG. 1;

FIG. 5 is a top plan view of the patella clamp of FIG. 1; FIG. 6 is a bottom plan view of the patella clamp of FIG. 1; FIG. 7 is a rear perspective view of the patella clamp of FIG. 1;

FIG. 8 is a front perspective view of a design of another embodiment of the patella clamp;

FIG. 9 is a first side elevation view of the patella clamp of FIG. 8, the second side elevation view of the patella clamp being a mirror image of the first side elevation view shown in FIG. 9;

FIG. 10 is a rear elevation view of the patella clamp of FIG. 8;

FIG. 11 is a front elevation view of the patella clamp of FIG. 8;

FIG. 12 is a top plan view of the patella clamp of FIG. 8; FIG. 13 is a bottom plan view of the patella clamp of FIG. 8; and,

(Continued)

FIG. 14 is a rear perspective view of the patella clamp of FIG. 8.

The broken lines in the drawings are included for the purpose of illustrating portions of the patella clamp and form no part of the claimed design.

1 Claim, 10 Drawing Sheets
